FIG. 3

FIG. 4

FIG. 5

FIG. 6

FIG. 7

FIG. 8

FIG. 9

FIG. 10

FIG. 1 is a perspective view of a calculator or similar article showing my new design in operative condition;

FIG. 2 is a perspective view with the cover in place and the display panel closed;

FIG. 3 is a top plan view thereof;

FIG. 4 is a top plan view in operative condition;

FIG. 5 is a bottom plan view;

FIG. 6 is a front elevational view with the cover in place and the display panel closed;

FIG. 7 is a right side elevational view thereof;

FIG. 8 is a front elevational view in operative condition;

FIG. 9 is a right side elevational view thereof; and

FIG. 10 is a rear elevational view with the display panel closed.

I claim:

The ornamental design for calculator or similar article, substantially as shown.
